SCREEN FOR CASTING RISERS

Edwin T. Myskowski and Howard F. Taylor,
Washington, D. C.

Application May 21, 1945, Serial No. 594,881

4 Claims. (Cl. 22—134)

(Granted under the act of March 3, 1883, as
amended April 30, 1928; 370 O. G. 757)

1

This invention relates to a method of and apparatus for casting, and more particularly to a method of and apparatus for facilitating the removal of risers from castings.

It is sometimes the practice in casting to employ a riser in order to obtain uniform distribution of the casting material throughout the casting chamber. Where certain hard metals are used for the casting material which are difficult to cut, such as some copper base alloys, or where the size or location of the riser precludes the use of power saws to remove the riser, the removal of the riser may become a very difficult operation involving the expenditure of considerable time and the possibility of damaging the casting.

An object of this invention is to provide an effective and efficient method of and apparatus for facilitating the removal of risers from castings.

In accordance with one embodiment of this invention, (prior to pouring the molten casting material into the mold) a perforated screen is located in the riser chamber substantially at the junction of the riser chamber and the casting chamber. After the casting material has been poured into the mold and has solidified, the casting and riser are removed from the mold. Since the perforated screen confines the area of connection between the casting and the riser to the perforations and thereby substantially reduces the area of connection between the riser and the casting, producing a plane of weakness, the riser may be readily broken off from the casting by striking it with a hammer or other suitable device.

Other objects and advantages of the present invention will be apparent from the following detailed description taken in conjunction with the drawings wherein:

Fig. 1 is a vertical sectional view of a casting mold having a perforated screen located in the riser chamber in accordance with this invention; and,

Fig. 2 is a perspective view of a suitable screen.

Referring now to the drawings and particularly to Fig. 1 thereof, wherein is illustrated a conventional sand mold, such as may be used in the casting of metal but which is suitable for casting of other materials such as certain glasses and plastics which are formed by casting, it will be seen that the mold comprises a lower mold section 1, or drag, and an upper mold section 2, or cope, supported thereon. A vertically extending sprue passage 3 is formed in the sand 4, which fills the mold, and this passage connects with a horizontally extending runner passage 5. The

2

left end of the runner passage connects to a casting chamber 6, formed in the sand and having the desired internal configuration. At the upper end of the casting chamber 6 is formed a riser chamber 7, the sides of which may be flared outwardly slightly, as shown. In order to facilitate pouring, a funnel-shaped pouring basin 8 may be located at the entrance of the sprue passage 3.

In using a mold, such as that illustrated, the molten casting material may be poured into the pouring basin 8; it then runs down the sprue passage 3, then along the runner passage 5 and enters the casting chamber 6, gradually filling the casting chamber 6 and the riser chamber 7, entering the riser chamber while still in a molten condition. The weight of the molten material in the riser chamber aids in the feeding or distribution of the material throughout the casting chamber.

After the pouring operation has been completed, the casting material is permitted to solidify and the casting and riser are then removed from the mold. Thereafter, ordinarily it is a simple matter to remove the runner and sprue portions of the casting merely by breaking them off, since their cross-sectional size is relatively small. However, the cross-sectional size of the riser, particularly in the plane of the junction of the riser and the casting is ordinarily quite large and may be, as shown in Fig. 1, the same size as the diameter of the casting chamber. Accordingly, the riser in many cases may not be readily broken off, but must be removed by sawing or chipping with a pneumatic hammer. Where the casting material is difficult to cut or to chip, or as hereinbefore stated where the location of the riser is such that access to the riser with a power saw is precluded, the removal of the riser may present considerable difficulty.

In accordance with this invention, a perforated screen 10 is located in the riser chamber at the junction between the riser chamber 7 and the casting chamber 6. The material used for the screen must be, of course, one which will not be melted at the temperature of the casting operation, and which will not alloy with or fuse to the casting material. Accordingly high melting point metals or refractory or ceramic materials may be employed, or combinations of these such as a metal screen having a coating of refractory material. Where a metal screen is employed without a refractory coating, it may be desirable to coat or plate the surface of the metal with a corrosion resistant material such as tin. While the size of the perforations in the screen and the

number of the perforations per square inch is not critical, sufficient open space must be provided in the screen to permit the molten material to pass readily therethrough and, at the same time, the area of connection between the riser and the casting must be sufficiently reduced to permit easy removal of the casting from the riser, by breaking the riser off the casting. In practice it has been found that if the openings comprise about 30% of the total screen area, sufficient passage is provided for the molten material and at the same time the area of connection between the riser and the casting is adequately reduced to accomplish the purposes of the present invention. A screen having perforations .032 inch in diameter, and 144 such perforations per square inch has been found to provide a satisfactory balance between these two desiderata in casting manganese bronze alloys. However, with other casting materials having different viscosities at casting temperatures which are employed, it may be desirable to increase or to decrease the size of the perforations and/or the relative size of the total perforated area to the unperforated area.

It has sometimes been found desirable to form an aperture 11 in the center of the screen 10, which may be approximately $\frac{1}{4}$ the diameter of the screen, to permit the molten material to seep through the screen as it cools and reaches a highly viscous state. This also aids in preventing sagging of the screen. Where the perforated screen 10 is to be used in a top pouring operation, that is, where no runner passage 5 is provided and the molten material is poured through the riser chamber into the casting chamber, the provision of the aperture 11 in the center of the screen is not required.

In order to prevent the weight of the material in the riser chamber from causing the screen 10 to sag downwardly into the casting chamber during the casting operation, it has been found desirable in some cases to curve the cross portion of the screen upward, as shown, to provide a convex surface in the riser chamber. It will be apparent that by curving the cross portion of the screen upwardly as shown, the weight of the material in the riser chamber while it will tend to force the screen downwardly will also force the periphery of the screen outwardly against the sides of the riser chamber, thereby tending to retain the screen in position. It has been found that a radius of curvature of the cross portion of the screen equivalent to five times the radius of the riser chamber provides a satisfactory convex surface and at the same time does not involve a substantial increase in the area of connection between the riser and the casting.

The outer peripheral portion of the screen 10 may be bent outwardly in some cases to form outwardly flared sides 12 as clearly shown in Fig. 2. The sides 12 engage the sides of the riser chamber and aid in retaining the screen in position in the chamber where actual embedding of the screen or other methods of supporting the screen at the junction of the casting and the riser are difficult or impractical.

Where difficulty is encountered in removing the sprue from the casting, it would, of course, be feasible to insert a screen such as described adjacent the gate to facilitate removal of the sprue. Such a screen may be employed in addition to the screen employed at the base of the riser.

In practice in the casting of metals it has been found that removal of the riser from the casting is somewhat easier if the casting is removed from the mold as soon as the temperature of the casting is below the visible heat range and the riser is broken off at that time. This is believed to be due to the fact that at the lower end of the visible heat range while the metal is then solid, it possesses relatively lower strength and resistance to breakage than when completely cooled, that is to say, it is more brittle.

While but one embodiment of this invention has been shown and described, it will be understood that many changes and modifications may be made therein without departing from the spirit or the scope of the present invention, which is limited only by the appended claims.

The invention described herein may be manufactured or used by or for the Government of the United States of America for governmental purposes without the payment of any royalties thereon or therefor.

What is claimed is:

1. In a casting apparatus having a riser chamber and a casting chamber, a convex perforated screen interposed between said riser chamber and said casting chamber and having an aperture formed in the central portion thereof several times larger than the perforations in the screen and approximately one-fourth the diameter of the screen to facilitate passage of casting material between the riser chamber and the casting chamber.
2. In a casting apparatus having a riser chamber and a casting chamber, a convex, perforated screen interposed between said casting chamber and said riser chamber, the curved portion of said screen extending into said riser chamber away from the plane of junction between the riser and casting chambers.
3. In a casting apparatus having a riser chamber and a casting chamber, a convex, perforated screen interposed between said casting chamber and said riser chamber and having its periphery located substantially at the junction between said riser chamber and said casting chamber, the curved portion of said screen extending into said riser chamber away from the casting chamber.
4. In a casting apparatus having a riser chamber and a casting chamber, a convex, metallic perforated screen interposed between said casting chamber and said riser chamber, the outer peripheral portion of said screen being bent upwardly and outwardly so as to wedge against the inner side of the riser chamber and aid in retaining the screen in position on the chamber.
